HEDGE SHEARS

John D. Olson, Farmington, Conn., assignor to The Stanley Works, New Britain, Conn., a corporation of Connecticut

Filed Sept. 27, 1965, Ser. No. 87,187

Term of patent 14 years

(Cl. D22—4)

FIG. 1 is a top plan view of a pair of hedge shears showing my new design;

FIG. 2 is a side elevational view thereof;

FIG. 3 is a bottom view thereof; and

FIG. 4 is a top view thereof showing the shears in open position.

I claim:

The ornamental design for hedge shears, as shown.
